MICHAEL F. LOWTH AND THOMAS J. HOWE, OF OWATONNA, MINNESOTA

Letters Patent No. 64,119, dated April 23, 1867.

IMPROVEMENT IN CULTIVATORS.

The Schedule referred to in these Letters Patent and making part of the same.

TO ALL WHOM IT MAY CONCERN:

Be it known that we, MICHAEL F. LOWTH and THOMAS J. HOWE, of Owatonna, in the county of Steele, and State of Minnesota, have invented a new and useful Improvement in Cultivators; and we do hereby declare the following to be a full, clear, and exact description of the same, reference being had to the accompanying drawings, which are made a part of this specification, and in which—

Figure 1 is a plan of a cultivator illustrating our improvement.

Figure 2 is a vertical longitudinal section of the same.

Figure 3 is a view embracing in detail the several parts which are concerned in the elevation of the shovels.

This invention relates to a cultivator in which the shovel-beams have pivoted attachment upon a rod, and are connected to a transverse bar so as to be susceptible of elevation by means of chains or ropes which run over grooved quadrants upon the opposite ends of a journalled shaft, said quadrants being vibrated by means of a lever.

The object of the invention is to enable the position of the lever to be changed so as to adapt it to be operated by a person either riding on the seat of the implement or walking behind the same.

In order that others skilled in the art to which our invention appertains may be enabled to fully understand and use the same, we will proceed to describe its construction and operation.

The machine proper, consisting of the wheels A, frame B, tongue C, seat E, and shovel-beams D, may be constructed in the manner represented in the drawings, or with such modifications as may be found desirable, no specific description being needed in connection therewith, as the present improvement has reference only to the means for elevating the shovels. At their forward ends the shovel-beams D are held by a transverse rod, F, which, passing through the ends of the beams, forms a pivot upon which the beams are free to turn. The rod F is supported in the enlargements upon the bars G, which are secured to the transverse bars of the frame B B. The rear ends of the beams D are connected by screws, bolts, or otherwise, to the transverse bar H. H may represent chains (or ropes) attached at one end by staples to the bar H, and hitched each to a hook on the quadrants J J', which are attached to the opposite ends of the shaft K, the latter being mounted and adapted to turn in the brackets or supports L L'. By vibrating one of the quadrants J the shaft K is partially rotated, and the other quadrant is consequently vibrated simultaneously. The circular rims of the quadrants J J' are grooved so as to confine and act with the requisite tensional draught upon the chains I to elevate the bar H together with the shovel-beams D. M (see fig. 3) is a segmental plate which, as well as the quadrants, may be of cast iron, and which is formed with a circular aperture to adapt it to be fitted upon the hub j of one of the quadrants. The segment M is also cast with sockets m m, which confine the lower end of the lever N. The said segment being contiguous to the inner face of the bracket L, (see fig. 1,) is coupled or connected with the quadrant J by means of the screw-bolt O. The position of the segment M, in relation to the quadrant J, may be varied by changing the bolt O from one of the apertures j¹ j² to the other. Thus, when the screw-bolt O occupies the aperture j¹ the lever N will stand in a position to be conveniently operated by the person upon the seat E, but when the said bolt occupies the aperture j² the rear end of the lever N will be sufficiently depressed to enable it to be grasped and operated by a person following the machine on foot. It will be seen that under either of the positions which the segment M may thus be made to assume, a given movement of the lever causes the quadrants to vibrate to the same extent, and that the adjustment of the segment is effected without changing the normal relation between the segment J and its attachment with the elevating bar H. The projections m' m' on the segment M serve as guides by moving in contact with the upper circular rim of the bracket L. The apertures l in the bracket L merely reduce the weight, but the apertures l' are designed to receive the end of the pin n on the lever N, which pin may be thrown into either of said apertures by the lateral impulse of the lever N, and enables the latter to be held at different points to retain the shovels in any desired position.

Having thus described our invention, what we claim as new herein, and desire to secure by Letters Patent, is—

1. The combination with the quadrant J of the adjustable segment M for the purpose of changing the position of the lever N, substantially as and for the object specified.
2. The combination of the quadrants J J', segment M, shaft K, and lever N with the chains or flexible connections I, connecting-bar H, and shovel-beams D, all arranged and operating in the manner and for the purpose specified.

MICHAEL F. LOWTH,
THOMAS J. HOWE.
